(57) CLAIM

The ornamental design for a mold, as shown and described.

DESCRIPTION

FIG. 1 is a front elevation view of a mold showing my new design;

FIG. 2 is a right side elevation view thereof;

FIG. 3 is a rear elevation view thereof;

FIG. 4 is a left elevation view thereof; and,

FIG. 5 is a top plan view thereof.

The bottom surface of the mold is flat and unornamented.
